UNITED STATES PATENT OFFICE

143,504

DESIGN FOR A ROTARY WING AIRCRAFT

Joseph S. Pecker and Agnew E. Larsen,
Philadelphia, Pa.

Application July 10, 1944, Serial No. 114,353

Term of patent 3½ years

(Cl. D71—1)

To all whom it may concern:

Be it known that we, Joseph S. Pecker and Agnew E. Larsen, citizens of the United States and residents of Philadelphia, in the county of Philadelphia and State of Pennsylvania, have invented a new, original and ornamental Design for Rotary Wing Aircraft, of which the following is a specification, reference being had to the accompanying drawing, forming part thereof, in which

Figure 1 is a side perspective view of the inven-

tion showing the rotary wing aircraft in flight with the landing gear retracted, and

Figure 2 is a top view, partly in perspective, of the invention, showing the rotary wing aircraft grounded and with the landing gear extended.

We claim:

The ornamental design for a rotary wing aircraft, substantially as shown and described.

JOSEPH S. PECKER.
AGNEW E. LARSEN.
